(57) **ABSTRACT**

A system configured to create a flexible home theater group using a variety of different devices. To enable synchronized audio output, the system performs device localization to generate map data representing locations of the devices. The system determines distance values between devices using timing information generated during calibration even when the devices themselves may not have synchronized clocks. During calibration, each device will generate a calibration tone in a particular order, enabling listening devices to detect the calibration tone and determine a relative direction of the output device. The listening devices also generate timing information indicating when each calibration tone was detected which can be used to determine a propagation delay that corresponds to a distance between the output device and the listening device. Using the relative directions and the distance values, the primary device can generate a device map that enables the home theater to render output audio correctly.

BACKGROUND

With the advancement of technology, the use and popularity of electronic devices has increased considerably. Electronic devices are commonly used to capture and process audio data.

BRIEF DESCRIPTION OF DRAWINGS

For a more complete understanding of the present disclosure, reference is now made to the following description taken in conjunction with the accompanying drawings.

FIG. 1 is a conceptual diagram illustrating a system configured to perform multi-device localization and ranging according to embodiments of the present disclosure.

FIG. 2 illustrates an example of a flexible home theater according to embodiments of the present disclosure.

FIG. 3 illustrates an example component diagram for rendering audio data in a flexible home theater according to embodiments of the present disclosure.

FIG. 4 illustrates an example component diagram for performing multi-device localization and rendering according to embodiments of the present disclosure.

FIG. 5 illustrates examples of calibration sound playback and calibration sound capture according to embodiments of the present disclosure.

FIG. 6 is a communication diagram illustrating an example of performing multi-device localization according to embodiments of the present disclosure.

FIG. 7 is a communication diagram illustrating an example of performing localization by an individual device according to embodiments of the present disclosure.

FIG. 8 illustrates an example component diagram for performing angle of arrival estimation according to embodiments of the present disclosure.

FIG. 9 illustrates an example component diagram for performing multi-device localization and device map generation according to embodiments of the present disclosure.

FIGS. 10A-10B illustrate examples of calibration sound playback and calibration sound capture according to embodiments of the present disclosure.

FIGS. 11A-11C illustrate examples of calibration timing information that is used to determine distance values according to embodiments of the present disclosure.

FIG. 12 illustrates an example component diagram for performing device mapping according to embodiments of the present disclosure.

FIG. 13 illustrates an example component diagram for performing distance estimation according to embodiments of the present disclosure.

FIGS. 14A-14B illustrate examples of performing cross-correlation to detect first peaks used to generate timing information according to embodiments of the present disclosure.

FIG. 15 is a flowchart conceptually illustrating an example method for performing distance estimation according to embodiments of the present disclosure.

FIG. 16 is a block diagram conceptually illustrating example components of a device, according to embodiments of the present disclosure.

FIG. 17 is a block diagram conceptually illustrating example components of a system, according to embodiments of the present disclosure.

FIG. 18 illustrates an example of a computer network for use with the overall system, according to embodiments of the present disclosure.

DETAILED DESCRIPTION

Electronic devices may be used to capture input audio and process input audio data. The input audio data may be used for voice commands and/or sent to a remote device as part of a communication session. In addition, the electronic devices may be used to process output audio data and generate output audio. The output audio may correspond to the communication session or may be associated with media content, such as audio corresponding to music or movies played in a home theater. Multiple devices may be grouped together in order to generate output audio using a combination of the multiple devices.

To enable synchronized audio output, devices, systems and methods are disclosed that perform multi-device localization and ranging to generate map data representing a device map. The system may create a flexible home theater group using a variety of different devices, and may perform the multi-device localization to generate the map data, which represents locations of devices in the home theater group. The system determines distance values between devices using timing information generated during calibration even when the devices themselves may not have synchronized clocks. During calibration, each device will generate a calibration tone in a particular order, enabling listening devices to detect the calibration tone and determine a relative direction of the output device. The listening devices also generate timing information indicating when each calibration tone was detected which can be used to determine a propagation delay that corresponds to a distance between the output device and the listening device. Using the relative directions and the distance values, the primary device can generate a device map, which enables the home theater to render output audio correctly.

FIG. 1 is a conceptual diagram illustrating a system configured to perform multi-device localization and ranging according to embodiments of the present disclosure. As illustrated in FIG. 1, a system 100 may include multiple devices 110a/110b/110c/110d connected across one or more networks 199. In some examples, the devices 110 (local to a user) may also be connected to a remote system 120 across the one or more networks 199, although the disclosure is not limited thereto.

The device 110 may be an electronic device configured to capture and/or receive audio data. For example, the device 110 may include a microphone array configured to generate input audio data, although the disclosure is not limited thereto and the device 110 may include multiple microphones without departing from the disclosure. As is known and used herein, “capturing” an audio signal and/or generating audio data includes a microphone transducing audio waves (e.g., sound waves) of captured sound to an electrical signal and a codec digitizing the signal to generate the microphone audio data. In addition to capturing the input audio data, the device 110 may be configured to receive output audio data and generate output audio using one or more loudspeakers of the device 110. For example, the device 110 may generate output audio corresponding to media content, such as music, a movie, and/or the like.

As illustrated in FIG. 1, the system 100 may include four separate devices 110a-110d, which may be included in a flexible home theater group, although the disclosure is not limited thereto and any number of devices may be included

in the flexible home theater group without departing from the disclosure. For example, a user may group the four devices as part of the flexible home theater group and the system 100 may select one of the four devices 110a-110d as a primary device that is configured to synchronize output audio between the four devices 110a-110d. In the example illustrated in FIG. 1, the first device 110a is the primary device and the second device 110b, the third device 110c, and the fourth device 110d are the secondary devices, although the disclosure is not limited thereto.

In some examples, the first device 110a may receive a home theater configuration. For example, the user may use a smartphone or other devices and may input the home theater configuration using a user interface. However, the disclosure is not limited thereto, and the system 100 may receive the home theater configuration without departing from the disclosure. In response to the home theater configuration, the first device 110a may generate calibration data indicating a sequence for generating playback audio, may send the calibration data to each device in the home theater group, and may cause the devices to perform the calibration sequence. For example, the calibration data may indicate that the first device 110a may generate a first audible sound during a first time range, the second device 110b may generate a second audible sound during a second time range, the third device 110c may generate a third audible sound during a third time range, and that the fourth device 110d may generate a fourth audible sound during a fourth time range. In some examples there are gaps between the audible sounds, such that the calibration data may be include values of zero (e.g., padded with zeroes between audible sounds), but the disclosure is not limited thereto and the calibration data may not include gaps without departing from the disclosure.

During the calibration sequence, a single device 110 may generate an audible sound and the remaining devices may capture the audible sound in order to determine a relative direction and/or distance. For example, when the first device 110a generates the first audible sound, the second device 110b may capture the first audible sound by generating first audio data including a first representation of the first audible sound. Thus, the second device 110b may perform localization (e.g., sound source localization (SSL) processing and/or the like) using the first audio data and determine a first position of the first device 110a relative to the second device 110b. Similarly, the third device 110c may generate second audio data including a second representation of the first audible sound. Thus, the third device 110c may perform localization using the second audio data and may determine a second position of the first device 110a relative to the third device 110c. Each of the devices 110 may perform these steps to generate audio data and/or determine a relative position of the first device 110a relative to the other devices 110, as described in greater detail below with regard to FIGS. 5-6.

For ease of illustration, the disclosure may refer to the devices generating a calibration tone, such as an audible sound, during the calibration sequence. However, the disclosure is not limited thereto, and the calibration tone may be an inaudible sound without departing from the disclosure. Thus, the system 100 may generate the calibration tone as an ultrasonic sound and/or the like without departing from the disclosure.

As illustrated in FIG. 1, the first device 110a may send (130) calibration data to secondary devices and may receive (132) timing information from the secondary devices, as described in greater detail below with regard to FIG. 3. For

example, the first device 110a may send calibration data indicating an order (e.g., calibration sequence) in which the devices 110 may generate an audible sound, such as a calibration tone. In response to the calibration data, the devices 110 may perform the calibration sequence and capture the audible sounds generated by all of the other devices 110. The devices 110 may then generate timing information associated with when the audible sounds were detected and send the timing information back to the first device 110a.

The first device 110a may determine (134) time differences represented in the timing information and may determine (136) distance values between secondary devices using the time differences, as described in greater detail below with regard to FIGS. 11A-11C. For example, to determine a distance between the second device 110b and the third device 110c, the first device 110a may determine a first time difference between when the second device 110b detected a second audible sound generated by the second device 110b and when the second device 110b detected a third audible sound generated by the third device 110c. Similarly, the first device 110a may determine a second time difference between when the third device 110c detected the second audible sound generated by the second device 110b and when the third device 110c detected the third audible sound generated by the third device 110c. By subtracting the second time difference from the first time difference and dividing in half, the first device 110a may determine a propagation delay from the second device 110b to the third device 110c and a corresponding distance value. Thus, the first device 110a may perform similar processing between each pair of devices to determine the distance values.

The first device 110a may generate (138) map data using the distance values. For example, the first device 110a may generate map data indicating locations of each of the devices 110 included in the home theater group. In some examples, the first device 110a may generate the map data with the center point corresponding to a listening position of a user, such that coordinate values of each of the locations in the map data indicate a position relative to the listening position. Additionally or alternatively, the first device 110a may generate the map data with the television along a vertical axis from the listening position, such that a look direction from the listening position to the television extends vertically along the vertical axis, although the disclosure is not limited thereto.

After generating the map data, the first device 110a may send (140) the map data to a rendering component to generate rendering coefficient values, as described in greater detail below with regard to FIG. 3. For example, the rendering component may process the map data and determine rendering coefficient values for each of the devices 110a-110d included in the home theater group.

As used herein, audio signals or audio data (e.g., microphone audio data, or the like) may correspond to a specific range of frequency bands. For example, the audio data may correspond to a human hearing range (e.g., 20 Hz-20 kHz), although the disclosure is not limited thereto.

As used herein, a frequency band (e.g., frequency bin) corresponds to a frequency range having a starting frequency and an ending frequency. Thus, the total frequency range may be divided into a fixed number (e.g., 256, 512, etc.) of frequency ranges, with each frequency range referred to as a frequency band and corresponding to a uniform size. However, the disclosure is not limited thereto and the size of the frequency band may vary without departing from the disclosure.

The device 110 may include multiple microphones configured to capture sound and pass the resulting audio signal created by the sound to a downstream component. Each individual piece of audio data captured by a microphone may be in a time domain. To isolate audio from a particular direction, the device may compare the audio data (or audio signals related to the audio data, such as audio signals in a sub-band domain) to determine a time difference of detection of a particular segment of audio data. If the audio data for a first microphone includes the segment of audio data earlier in time than the audio data for a second microphone, then the device may determine that the source of the audio that resulted in the segment of audio data may be located closer to the first microphone than to the second microphone (which resulted in the audio being detected by the first microphone before being detected by the second microphone).

Using such direction isolation techniques, a device 110 may isolate directionality of audio sources. A particular direction may be associated with azimuth angles divided into bins (e.g., 0-45 degrees, 46-90 degrees, and so forth). To isolate audio from a particular direction, the device 110 may apply a variety of audio filters to the output of the microphones where certain audio is boosted while other audio is damped, to create isolated audio corresponding to a particular direction, which may be referred to as a beam. While in some examples the number of beams may correspond to the number of microphones, the disclosure is not limited thereto and the number of beams may be independent of the number of microphones. For example, a two-microphone array may be processed to obtain more than two beams, thus using filters and beamforming techniques to isolate audio from more than two directions. Thus, the number of microphones may be more than, less than, or the same as the number of beams. The beamformer unit of the device may have an adaptive beamformer (ABF) unit/fixed beamformer (FBF) unit processing pipeline for each beam, although the disclosure is not limited thereto.

FIG. 2 illustrates an example of a flexible home theater according to embodiments of the present disclosure. As illustrated in FIG. 2, a flexible home theater 200 may comprise a variety of devices 110 without departing from the disclosure. For example, FIG. 2 illustrates an example home theater that includes a first device 110a (e.g., television or headless device associated with the television) at a first location, a second device 110b (e.g., speech-enabled device with a screen) at a second location below the television, a third device 110c (e.g., speech-enabled device with a screen) at a third location to the right of a listening position 210 of the user, and a fourth device 110d (e.g., speech-enabled device) at a fourth location to the left of the listening position 210. However, the disclosure is not limited thereto and the flexible home theater 200 may include additional devices 110 without departing from the disclosure. Additionally or alternatively, the flexible home theater 200 may include fewer devices 110 and/or the locations of the devices 110 may vary without departing from the disclosure.

Despite the flexible home theater 200 including multiple different types of devices 110 in an asymmetrical configuration relative to the listening position 210 of the user, the system 100 may generate playback audio optimized for the listening position 210. For example, the system 100 may generate map data indicating the locations of the devices 110, the type of devices 110, and/or other context (e.g., number of loudspeakers, frequency response of the drivers, etc.), and may send the map data to a rendering component. The rendering component may generate individual renderer

coefficient values for each of the devices 110, enabling each individual device 110 to generate playback audio that takes into account the location of the device 110 and characteristics of the device 110 (e.g., frequency response, etc.).

To illustrate a first example, the second device 110b may act as a center channel in the flexible home theater 200 despite being slightly off-center below the television. For example, first renderer coefficient values associated with the second device 110b may adjust the playback audio generated by the second device 110b to shift the sound stage to the left from the perspective of the listening position 210 (e.g., centered under the television). To illustrate a second example, the third device 110c may act as a right channel and the fourth device 110d may act as a left channel in the flexible home theater 200, despite being different distances from the listening position 210. For example, second renderer coefficient values associated with the third device 110c and fourth renderer coefficient values associated with the fourth device 110d may adjust the playback audio generated by the third device 110c and the fourth device 110d such that the two channels are balanced from the perspective of the listening position 210.

FIG. 3 illustrates an example component diagram for rendering audio data in a flexible home theater according to embodiments of the present disclosure. As illustrated in FIG. 3, the system 100 may perform flexible home theater rendering 300 to generate individual flexible renderer coefficient values for each of the devices 110 included in the flexible home theater group. First, the system 100 may cause each device 110 included in the flexible home theater group to generate measurement data during a calibration sequence, as will be described in greater detail below with regard to FIG. 6. For example, a first device (e.g., Device1) may generate first measurement data 310a, a second device (e.g., Device2) may generate second measurement data 310b, and a third device (e.g., Device3) may generate third measurement data 310c. While the example illustrated in FIG. 3 only includes three devices 110 in the flexible home theater, the disclosure is not limited thereto and the flexible home theater may have any number of devices 110 without departing from the disclosure.

The first device may generate the first measurement data 310a by generating first audio data capturing one or more audible sounds and performing sound source localization processing to determine direction(s) associated with the audible sound(s) represented in the first audio data. For example, if the second device is generating first playback audio during a first time range, the first device may capture a representation of the first playback audio and perform sound source localization processing to determine that the second device is in a first direction relative to the first device, although the disclosure is not limited thereto. Similarly, the second device may generate the second measurement data 310b by generating second audio data capturing one or more audible sounds and performing sound source localization processing to determine direction(s) associated with the audible sound(s) represented in the second audio data. For example, if the third device is generating second playback audio during a second time range, the second device may capture a representation of the second playback audio and perform sound source localization processing to determine that the third device is in a second direction relative to the second device, although the disclosure is not limited thereto.

As illustrated in FIG. 3, a device mapping component 320 may receive the measurement data 310 and may generate device map data representing a device map and/or generate listening position data indicating the listen-

ing position 210 associated with the user. For example, a primary device (e.g., mapping coordinator) may receive the measurement data 310 from secondary devices and may process the measurement data 310 to generate the device map indicating a location of each of the devices 110 in the flexible home theater group. Additionally or alternatively, the mapping compute component 320 may receive measurement data 310 corresponding to the user (e.g., user localization) and may process the measurement data 310 to determine the listening position 210 associated with the user, as will be described in greater detail below with regard to FIG. 6.

The device mapping compute component 320 may output the device map data and/or the listening position data to a renderer coefficient generator component 330 that is configured to generate the flexible renderer coefficient values. In addition, the renderer coefficient generator component 330 may receive device descriptors associated with each of the devices 110 included in the flexible home theater group. For example, the renderer coefficient generator component 330 may receive a first description 325a corresponding to the first device (e.g., Device1), a second description 325b corresponding to the second device (e.g., Device2), and a third description 325c corresponding to the third device (e.g., Device3).

In some examples, the renderer coefficient generator component 330 may receive these descriptions directly from each of the devices 110 included in the flexible home theater group. However, the disclosure is not limited thereto, and in other examples the renderer coefficient generator component 330 may receive the descriptions from a single device (e.g., storage component, remote system 120, etc.) without departing from the disclosure. For example, the renderer coefficient generator component 330 may receive the device descriptions from the device mapping compute component 320 without departing from the disclosure.

The renderer coefficient generator component 330 may process the device map, the listening position, the device descriptions, and/or additional information (not illustrated) to generate flexible renderer coefficient values for each of the devices 110 included in the flexible home theater group. For example, the renderer coefficient generator component 330 may generate first renderer coefficient data 335a (e.g., first renderer coefficient values) for a first local renderer 340a associated with the first device, second renderer coefficient data 335b (e.g., second renderer coefficient values) for a second local renderer 340b associated with the second device, and third renderer coefficient data 335c (e.g., third renderer coefficient values) for a third local renderer 340c associated with the third device, although the disclosure is not limited thereto. As illustrated in FIG. 4, each of the devices 110 may include a local renderer 340 configured to apply the flexible renderer coefficient values calculated for the individual device in order to generate the playback audio.

FIG. 4 illustrates an example component diagram for performing multi-device localization and rendering according to embodiments of the present disclosure. In some examples, the system 100 may receive input data indicating two or more devices 110 to include in a flexible home theater group. For example, the user may select which device 110 to include in the flexible home theater group using a touch-screen device 102 (e.g., smartphone), although the disclosure is not limited thereto. The system 100 may receive the flexible home theater group selection indicated by the input data and may send instructions to each of the devices included in the flexible home theater group in order to form

the flexible home theater group and designate one of the devices as a primary device 410. Thus, the primary device 410 coordinates with the remaining devices (e.g., secondary devices 412) to generate synchronized playback audio.

As illustrated in FIG. 4, an audio playback control plane 400 includes synchronization components 420 integrated with each device 110 included in the flexible home theater group. For example, FIG. 4 illustrates an example in which the flexible home theater group includes a primary device 410 that includes a first synchronization component 420a, a first secondary device 412a that includes a second synchronization component 420b, and a second secondary device 412b that includes a third synchronization component 420c, although the disclosure is not limited thereto. The synchronization components 420 may synchronize audio between each of the devices 110 included in the flexible home theater group so that the user perceives synchronized playback audio (e.g., playback audio reaches the user without time delays or other issues that reduce audio quality). For example, the synchronization components 420 may synchronize a system clock and/or timing between the devices 110 and controls when the audio is generated by each of the devices 110.

During audio playback, the synchronization component 420 may send unprocessed audio data to a flexible renderer component 430, which may perform rendering to generate processed audio data and may send the processed audio data to a playback controller 440 for audio playback. For example, the flexible renderer component 430 may render the unprocessed audio data using the flexible renderer coefficient values calculated by the renderer coefficient generator component 330, as described above with regard to FIG. 3.

To illustrate an example of generating first playback audio, a first flexible renderer component 430a associated with the primary device 410 may receive configuration data (e.g., first flexible renderer coefficient values and/or the like) and first unprocessed audio data from the first synchronization component 420a. The first flexible renderer component 430a may render the first unprocessed audio data using the first flexible renderer coefficient values to generate first processed audio data. The first flexible renderer component 430a may send the first processed audio data to a first playback controller component 440a, which may also receive first control information from the first synchronization component 420a. Based on the first control information, the first playback controller component 440a may generate first playback audio using first loudspeakers associated with the primary device 410. In some examples, such as during the calibration sequence, the first playback controller component 440a may generate first measurement data corresponding to relative measurements and may send the first measurement data to the first synchronization component 420a.

Similarly, the first secondary device 412a may generate second playback audio using the second synchronization component 420b, a second flexible renderer component 430b, and a second playback controller component 440b. For example, the second flexible renderer component 430b may receive second unprocessed audio data from the second synchronization component 420b and may render the second unprocessed audio data using second flexible renderer coefficient values to generate second processed audio data. The second flexible renderer component 430b may send the second processed audio data to the second playback controller component 440b, which may also receive second control information from the second synchronization component 420b. Based on the second control information, the

second playback controller component **440b** may generate second playback audio using second loudspeakers associated with the first secondary device **412a**. In some examples, such as during the calibration sequence, the second playback controller component **440b** may generate second measurement data corresponding to relative measurements and may send the second measurement data to the second synchronization component **420b**. The second synchronization component **420b** may send the second measurement data to the first synchronization component **420a** associated with the primary device **410**.

The second secondary device **412b** may perform the same steps described above with regard to the first secondary device **412a** to generate third playback audio and/or third measurement data and send the third measurement data to the first synchronization component **420a**. While FIG. 4 illustrates an example including only three devices **110** in the flexible home theater group (e.g., primary device **410**, first secondary device **412a**, and second secondary device **412b**), this is intended to conceptually illustrate an example and the disclosure is not limited thereto. Thus, the flexible home theater group may include any number of secondary devices **412** that interface with the primary device **410** to generate playback audio without departing from the disclosure.

As illustrated in FIG. 4, the primary device **410** may include the device mapping compute component **320** and the renderer coefficient generator component **330** described above with regard to FIG. 3, although the disclosure is not limited thereto. In addition, the primary device **410** may include a mapping coordinator component **450** that is configured to generate calibration data (e.g., a calibration sequence or calibration schedule) and cause each of the secondary devices **412** to perform the calibration sequence based on the calibration data. Thus, the mapping coordinator component **450** may generate the calibration data to indicate to the secondary devices **412** which individual device is expected to generate an audible sound at a particular time range. For example, the calibration data may indicate that the primary device **410** will generate a first audible sound during a first time range, the first secondary device **412a** will generate a second audible sound during a second time range following the first time range, and the second secondary device **412b** will generate a third audible sound during a third time range following the second time range.

While FIG. 4 illustrates an example in which the primary device **410** includes the device mapping compute component **320**, the renderer coefficient generator component **330**, and/or the mapping coordinator component **450**, the disclosure is not limited thereto. Instead, the primary device **410** may include the mapping coordinator component **450** and the device mapping compute component **320** and/or the renderer coefficient generator component **330** may be located on a separate device without departing from the disclosure. Additionally or alternatively, while FIG. 4 illustrates an example in which the primary device **410** is configured to generate the first audible sound, the disclosure is not limited thereto and the primary device **410** may not be configured to generate an audible sound without departing from the disclosure. For example, the primary device **410** may not include loudspeaker(s) and/or microphone(s) and therefore may not perform the calibration process described below without departing from the disclosure.

Based on the calibration data, the primary device **410** may generate the first audible sound during the first time range and each of the devices **410/412a/412b** may generate a first portion of respective measurement data corresponding to the

first audible sound. Similarly, the first secondary device **412a** may generate the second audible sound during the second time range and each of the devices **410/412a/412b** may generate a second portion of respective measurement data corresponding to the second audible sound. Finally, the second secondary device **412b** may generate the third audible sound during the third time range and each of the devices **410/412a/412b** may generate a third portion of respective measurement data corresponding to the third audible sound.

During the calibration sequence, the playback controller component **440** may receive calibration audio directly from the synchronization component **420**, bypassing the flexible renderer component **430**, which is illustrated in FIG. 4 as a dashed line. For example, the playback controller component **440** may receive raw audio data representing a calibration tone from the synchronization component **420** and may generate the audible sounds using this raw audio data. However, the disclosure is not limited thereto and the playback controller component **440** may receive the raw audio data from the synchronization component **420** via the flexible renderer component **430** (e.g., without any processing being performed by the flexible renderer component **430**) without departing from the disclosure.

After the first playback controller component **440a** of the primary device **410** generates the first measurement data, the first playback controller component **440a** may send the first measurement data to the device mapping compute component **320** via the first synchronization component **420a**. Similarly, after the second playback controller component **440b** of the first secondary device **412a** generates the second measurement data, the second synchronization component **420b** may send the second measurement data to the device mapping compute component **320** via the first synchronization component **420a**. Finally, after the third playback controller component **440c** of the second secondary device **412b** generates the third measurement data, the third synchronization component **420c** may send the third measurement data to the device mapping compute component **320** via the first synchronization component **420a**.

In some examples, the measurement data generated by the playback controller component **440** corresponds to the measurement data **310** described above with regard to FIG. 3. For example, the first playback controller component **440a** may generate Device1 measurement data **310a**, the second playback controller component **440b** may generate Device2 measurement data **310b**, and the third playback controller component **440c** may generate Device3 measurement data **310c**. However, the disclosure is not limited thereto, and in other examples the measurement data generated by the playback controller component **440** may be processed by another component to generate the measurement data **310**. For example, a first component within the primary device **410** (e.g., first synchronization component **420a** or a different component) may process the first measurement data to generate the Device1 measurement data **310a**, a second component within the first secondary device **412a** may process the second measurement data to generate the Device2 measurement data **310b**, and a third component within the second secondary device **412b** may process the third measurement data to generate the Device3 measurement data **310c**.

Additionally or alternatively, the primary device **410** may receive measurement data from the secondary devices **412** and may process the measurement data to generate the measurement data **310**. For example, a component of the primary device **410** may receive the first measurement data

from the first playback controller component 440a and may generate Device1 measurement data 310a, may receive the second measurement data from the first secondary device 412a and may generate the Device2 measurement data 310b, and may receive the third measurement data from the second secondary device 412b and may generate the Device3 measurement data 310c, although the disclosure is not limited thereto.

The device mapping compute component 320 may process the measurement data 310 to generate the device map data and/or the listening position data, as described in greater detail above with regard to FIG. 3. In addition, the renderer coefficient generator component 330 may process the device map data, the listening position data, and/or device description data 325 to generate the flexible renderer coefficient values 335. For example, the renderer coefficient generator component 330 may generate the first renderer coefficient data 335a (e.g., first renderer coefficient values) for the first flexible renderer component 430a associated with the primary device 410, second renderer coefficient data 335b (e.g., second renderer coefficient values) for the second flexible renderer component 430b associated with the first secondary device 412a, and third renderer coefficient data 335c (e.g., third renderer coefficient values) for the third flexible renderer component 430c associated with the second secondary device 412b.

FIG. 5 illustrates examples of calibration sound playback and calibration sound capture according to embodiments of the present disclosure. As illustrated in FIG. 5, the calibration data may indicate a calibration sequence illustrated by calibration sound playback 510. For example, a first device (Device1) may generate a first audible sound during a first time range, a second device (Device2) may generate a second audible sound during a second time range, a third device (Device3) may generate a third audible sound during a third time range, and a fourth device (Device4) may generate a fourth audible sound during a fourth time range.

The measurement data generated by each of the devices is represented in calibration sound capture 520. For example, the calibration sound capture 520 illustrates that while the first device (Device1) captures the first audible sound immediately, the other devices capture the first audible sound after variable delays caused by a relative distance from the first device to the capturing device. To illustrate a first example, the first device (Device1) may generate first audio data that includes a first representation of the first audible sound within the first time range and at a first volume level (e.g., amplitude). However, the second device (Device2) may generate second audio data that includes a second representation of the first audible sound after a first delay and at a second volume level that is lower than the first volume level. Similarly, the third device (Device3) may generate third audio data that includes a third representation of the first audible sound after a second delay and at a third volume level that is lower than the first volume level, and the fourth device (Device4) may generate fourth audio data that includes a fourth representation of the first audible sound after a third delay and at a fourth volume level that is lower than the first volume level.

Similarly, the second audio data may include a first representation of the second audible sound within the second time range and at a first volume level. However, the first audio data may include a second representation of the second audible sound after a first delay and at a second volume level that is lower than the first volume level, the third audio data may include a third representation of the second audible sound after a second delay and at a third

volume level that is lower than the first volume level, and the fourth audio data may include a fourth representation of the second audible sound after a third delay and at a fourth volume level that is lower than the first volume level.

As illustrated in FIG. 5, the third audio data may include a first representation of the third audible sound within the third time range and at a first volume level. However, the first audio data may include a second representation of the fourth audible sound after a first delay and at a second volume level that is lower than the first volume level, the second audio data may include a third representation of the fourth audible sound after a second delay and at a third volume level that is lower than the first volume level, and the fourth audio data may include a fourth representation of the fourth audible sound after a third delay and at a fourth volume level that is lower than the first volume level.

Finally, the fourth audio data may include a first representation of the fourth audible sound within the fourth time range at a first volume level. However, the first audio data may include a second representation of the second audible sound after a first delay and at a second volume level that is lower than the first volume level, the second audio data may include a third representation of the fourth audible sound after a second delay and at a third volume level that is lower than the first volume level, and the third audio data may include a fourth representation of the fourth audible sound after a third delay and at a fourth volume level that is lower than the first volume level. Based on the different delays and/or amplitudes, the system 100 may determine a relative position of each of the devices within the environment.

FIG. 6 is a communication diagram illustrating an example of performing multi-device localization according to embodiments of the present disclosure. As illustrated in FIG. 6, the primary device 410 may generate (610) a schedule for performing a calibration sequence, as described above with regard to FIG. 4. For example, the primary device 410 may generate calibration data to indicate to the secondary devices 412 which individual device is expected to generate an audible sound at a particular time range. For example, the calibration data may indicate that the primary device 410 will generate a first audible sound during a first time range, the first secondary device 412a will generate a second audible sound during a second time range, and the second secondary device 412b will generate a third audible sound during a third time range.

The primary device 410 may broadcast (612) the schedule to each of the secondary devices 412 and may start (614) the calibration sequence. For example, the primary device 410 may send the calibration data to the first secondary device 412a, to the second secondary device 412b, to a third secondary device 412c, and/or to any additional secondary devices 412 included in the flexible home theater group. Each of the devices 410/412 may start the calibration sequence based on the calibration data received from the primary device 410. For example, during the first time range the primary device 410 may generate the first audible sound while the secondary devices 412 generate audio data including representations of the first audible sound. Similarly, during the second time range the first secondary device 412a may generate the second audible sound while the primary device 410 and/or the secondary devices 412 generate audio data including representations of the second audible sound. In some examples, the primary device 410 and/or one of the secondary devices 412 may not include a microphone and therefore may not generate audio data during the calibration sequence. However, the other devices may still determine a

relative position of the primary device 410 based on the first audible sound generated by the primary device 410.

The primary device 410 may receive (616) calibration measurement data from the secondary devices 412. For example, the secondary devices 412 may process the audio data and generate the calibration measurement data by comparing a delay between when an audible sound was scheduled to be generated and when the audible sound was captured by the secondary device 412. To illustrate an example, the first secondary device 412a may perform sound source localization to determine an angle of arrival (AOA) associated with the second secondary device 412b, although the disclosure is not limited thereto. Additionally or alternatively, the first secondary device 412a may determine timing information associated with the secondary device 412b, which may be used to determine a distance between the first secondary device 412a and the second secondary device 412b, although the disclosure is not limited thereto. While not illustrated in FIG. 6, in some examples the primary device 410 may generate calibration measurement data as well, if the primary device 410 includes a microphone and is configured to generate audio data.

The primary device 410 may trigger (618) user localization and may receive (620) user localization measurement data from each of the secondary devices 412. For example, the primary device 410 may send instructions to the secondary devices 412 to perform user localization and the instructions may cause the secondary devices 412 to begin the user localization process. During the user localization process, the secondary devices 412 may be configured to capture audio in order to detect a wakeword or other audible sound generated by the user and generate the user localization measurement data corresponding to the user. For example, the system 100 may instruct the user to speak the wakeword from the user's desired listening position 210 and the user localization measurement data may indicate a relative direction and/or distance from each of the devices 410/412 to the listening position 210. While not illustrated in FIG. 6, in some examples the primary device 410 may also generate user localization measurement data if the primary device 410 includes a microphone and is configured to generate audio data.

While FIG. 6 illustrates an example in which the secondary devices 412 perform user localization and generate user localization measurement data, the disclosure is not limited thereto. In some examples, the system 100 may perform user localization using input data from other devices and/or sensors without departing from the disclosure. For example, the system 100 may know the location of the user based on location data associated with the device 102 (e.g., user may interact with the device 102 while the device 102 is at the listening position 210), location data generated using image data (e.g., computer vision processing identifying the user at the listening position 210), location data generated using distance sensors (e.g., distance sensors and/or other inputs identifying the user at the listening position 210), historical data (e.g., detecting speech from the listening position 210 over a prolonged period of time), and/or the like without departing from the disclosure. Thus, steps 618-620 may be optional without departing from the disclosure.

After receiving the calibration measurement data and the user localization measurement data, the primary device 410 may generate (622) device map data representing a device map for the flexible home theater group. For example, the primary device 410 may process the calibration measurement data in order to generate a final estimate of device

locations, interpolating between the calibration measurement data generated by individual devices 410/412. Additionally or alternatively, the primary device 410 may process the user localization measurement data to generate a final estimate of the listening position 210, interpolating between the user localization measurement data generated by individual devices 410/412.

If the flexible home theater group does not include a display such as a television, the primary device 410 may generate the device map based on the listening position 210, but an orientation of the device map may vary. For example, the primary device 410 may set the listening position 210 as a center point and may generate the device map extending in all directions from the listening position 210. However, if the flexible home theater group includes a television, the primary device 410 may set the listening position 210 as a center point and may select the orientation of the device map based on a location of the television. For example, the primary device 410 may determine the location of the television and may generate the device map with the location of the television extending along a vertical axis, although the disclosure is not limited thereto.

To determine the location of the television, in some examples the primary device 410 may generate calibration data instructing the television to generate a first audible noise using a left channel during a first time range and generate a second audible noise using a right channel during a second time range. Thus, each of the secondary devices 412 may generate calibration measurement data including separate calibration measurements for the left channel and the right channel, such that a first portion of the calibration measurement data corresponds to a first location associated with the left channel and a second portion of the calibration measurement data corresponds to a second location associated with the right channel. This enables the primary device 410 to determine the location of the television based on the first location and the second location, although the disclosure is not limited thereto.

FIG. 7 is a communication diagram illustrating an example of performing localization by an individual device according to embodiments of the present disclosure. As illustrated in FIG. 7, the primary device 400 may broadcast (612) the schedule to the first secondary device 412a and the first secondary device 412a may begin (710) the calibration sequence and generate audio data. For example, during the calibration sequence the first secondary device 412a may begin generate audio data capturing audible sounds generated by the primary device 410, the second secondary device 412b, the third secondary device 412c, and/or additional devices included in the flexible home theater group. In addition, the first secondary device 412a may generate (712) an audible sound based on the calibration schedule, which is also captured in the audio data generated by the first secondary device 412a. Thus, the first secondary device 412a generates audio data that includes a representation of each of the audible sounds generated during the calibration sequence.

Using this audio data, the first secondary device 412a may generate (714) calibration measurement data and may send (716) the calibration measurement data to the primary device 410. For example, the first secondary device 412a may perform sound source localization processing to determine a relative direction between the first secondary device 412a and the primary device 410, the second secondary device 412b, the third secondary device 412c, and/or any additional devices included in the flexible home theater group. Thus, the calibration measurement data may indicate

that the primary device 410 is in a first direction relative to the first secondary device 412a, that the second secondary device 412b is in a second direction relative to the first secondary device 412a, and that the third secondary device 412c is in a third direction relative to the first secondary device 412a. In some examples, the first secondary device 412a may determine timing information between the first secondary device 412a and the remaining devices, which the primary device 410 may use to determine distances between the first secondary device 412a and each of the other devices.

While FIG. 7 illustrates that the first secondary device 412a generates audio data in step 710 and generates calibration measurement data in step 714, the disclosure is not limited thereto. In some examples, the first secondary device 412a may not generate the audio data and/or the calibration measurement data without departing from the disclosure. For example, the first secondary device 412a may correspond to a television or other device that does not include a microphone. In this example, the television would still perform step 712 to generate an audible sound based on the calibration schedule, and in some examples would generate a first audible sound using a left channel and a second audible sound using a right channel, but would not generate the audio data and/or the calibration measurement data in steps 710 and 714 without departing from the disclosure.

After receiving the calibration measurement data, the primary device 410 may trigger (618) user localization and the first secondary device 412a may begin (720) the user localization process and generate audio data. For example, the first secondary device 412a may generate audio data and perform wakeword detection (e.g., keyword detection) and/or the like to detect speech generated by the user that is represented in the audio data. Once the first secondary device 412a detects the speech, the first secondary device 412a may generate (722) user localization measurement data indicating a relative direction and/or distance from the first secondary device 412a to the listening position 210 associated with the user and may send (724) the user localization measurement data to the primary device 410.

While FIG. 7 illustrates an example in which the secondary devices 412 perform user localization and generate user localization measurement data, the disclosure is not limited thereto. In some examples, the system 100 may perform user localization using input data from other devices and/or sensors without departing from the disclosure. For example, the system 100 may know the location of the user based on location data associated with the device 102 (e.g., user may interact with the device 102 while the device 102 is at the listening position 210), location data generated using image data (e.g., computer vision processing identifying the user at the listening position 210), location data generated using distance sensors (e.g., distance sensors and/or other inputs identifying the user at the listening position 210), historical data (e.g., detecting speech from the listening position 210 over a prolonged period of time), and/or the like without departing from the disclosure. Thus, step 618 and steps 720-724 may be optional without departing from the disclosure.

While FIG. 7 illustrates an example of the first secondary device 412a performing steps 710-724, this is intended to conceptually illustrate steps performed by any of the secondary devices 412. Thus, each of the secondary devices 412 (e.g., second secondary device 412b, third secondary device 412c, etc.) may be performing steps 710-724 to generate calibration measurement data and user localization measurement data without departing from the disclosure.

FIG. 8 illustrates an example component diagram for performing angle of arrival estimation according to embodiments of the present disclosure. As illustrated in FIG. 8, the system 100 may perform angle of arrival estimation 800 to determine an angle of arrival (e.g., device azimuth) and a corresponding variance, as well as timing information associated with the audible sounds captured during the calibration sequence. The system 100 may use the timing information to determine a distance between each of the devices.

The system 100 may begin the angle of arrival estimation 800 by receiving input audio data 805 and storing the input audio data 805 in a buffer component 810. The buffer component 810 may output the input audio data 805 to a first cross-correlation component 820 configured to perform a cross-correlation between the input audio data 805 and a calibration stimulus 815 to generate first cross-correlation data. For example, the cross-correlation component 820 may perform match filtering by determining a cross-correlation between the calibration stimulus 315 (e.g., calibration tone output by each device) and the input audio data 805 associated with each microphone.

The first cross-correlation component 820 sends the first cross-correlation data to a first peak detection and selection component 830 that is configured to identify first peak(s) represented in the first cross-correlation data and select a portion of the first cross-correlation data corresponding to the first peak(s). For example, the first peak detection and selection component 830 may locate peaks in the match filter outputs (e.g., first cross-correlation data) and select appropriate peaks by filtering out secondary peaks from reflections.

Using the selected first peak(s), the first peak detection and selection component 830 may generate timing data representing timing information that may be used by the device mapping compute component 320 to determine a distance between the devices. In some examples, the first peak detection and selection component 830 may generate the timing information that indicates a time associated with each individual peak detected in the first cross-correlation data. However, the disclosure is not limited thereto, and in other examples, the first peak detection and selection component 830 may determine a time difference between the peaks detected in the first cross-correlation data without departing from the disclosure. Thus, the timing information may include timestamps corresponding to the first peak(s), a time difference between peak(s), and/or the like without departing from the disclosure. In addition, the first peak detection and selection component 830 may send the selected peak(s) to a stimulus boundary estimation component 835 that is configured to determine a boundary corresponding to the stimulus represented in the input audio data 805.

The buffer component 810 may also output the input audio data 805 to an analysis filter bank component 840 that is configured to filter the input audio data 805 using multiple filters. The analysis filter bank component 840 may output the filtered audio data to a second cross-correlation component 850 that is configured to perform a second cross-correlation between the filtered audio data and acoustic wave decomposition (AWD) dictionary data 845 to generate second cross-correlation data.

A signal-to-noise ratio (SNR) frequency weighting component 855 may process the second cross-correlation data before a second peak detection and selection component 860 may detect second peak(s) represented in the second cross-correlation data and select a portion of the second cross-correlation data corresponding to the second peak(s). The

output of the second peak detection and selection component **860** is sent to a Kalman filter buffer component **870**, which stores second peak(s) prior to filtering. Finally, a Kalman filter component **875** may receive the estimated boundary generated by the stimulus boundary estimation component **835** and the second peak(s) stored in the Kalman filter buffer component **870** and may determine a device azimuth and/or a variance corresponding to the device azimuth.

While not illustrated in FIG. 8, each device may perform the steps for multiple microphones. For example, if the device includes four microphones, the timing information may include timestamps for each of the four microphones without departing from the disclosure. Thus, the timing information may include a timestamp for each audible sound (e.g., calibration tone) captured by each microphone, such that if there are three audible sounds (e.g., three separate devices generating a calibration tone), the timing information will include 12 timestamps (e.g., three timestamps for each of the four microphones). However, the disclosure is not limited thereto, and the number of microphones and/or the timestamps may vary. In some examples, the device may generate the timestamps using only a subset of the microphones without departing from the disclosure. For example, if the device includes eight microphones, the device may only determine timestamps using four of the microphones without departing from the disclosure. Additionally or alternatively, the device may generate timing information that corresponds to statistical information based on the timestamps. For example, the timing information may represent a mean (e.g., average) timestamp and a variance without departing from the disclosure.

Similarly, the device may determine the variance using multiple microphones. For example, four microphones may generate four separate measurements, and the device can generate an inter-microphone variance value to compare these measurements. Thus, a lower variance value may indicate that the results are more accurate (e.g., more consistency between microphones), whereas a higher variance value may indicate that the results are less accurate (e.g., at least one of the microphones is very different than the others).

While not illustrated in FIG. 8, in some examples the secondary devices **410** may include an additional component that is configured to consolidate the audio into a central point. For example, the additional component may process the audio data and/or cross correlation data generated by each of the microphones to determine a single timestamp for each peak, which may be included in the timing information sent to the primary device **410**. Thus, the primary device **410** may receive precise timing information from each of the secondary devices **412** and perform time difference of arrival (TDOA) estimation to generate TDOA data that may be used to generate the device map. In other examples, the additional component may be included in the primary device **410**, instead of the secondary devices **412**, without departing from the disclosure. For example, the additional component in the primary device **410** may receive the timing information from each of the secondary devices **412**, determine a central point for each secondary device **412**, and then perform the TDOA estimation.

FIG. 9 illustrates an example component diagram for performing multi-device localization and device map generation according to embodiments of the present disclosure. As illustrated in FIG. 9, the system **100** may perform device map generation **900** to process measurement data **910** generated by the devices **410/412** in order to generate device map data representing a device map for the flexible home

theater group. As described above with regard to FIG. 6, the device map data may include location(s) associated with each of the devices **410/412**, a location of a television, and/or a location of a listening position **210**. In some examples, the device map data may include additional information, such as device descriptors or other information corresponding to the devices **410/412** included in the device map.

As illustrated in FIG. 9, a matrix solver component **920** may receive the measurement data **910** from each of the devices **410/412**. For example, the matrix solver component **920** may receive first measurement data **910a** from a first device (e.g., Device1), second measurement data **910b** from a second device (e.g., Device2), and third measurement data **910c** from a third device **910c**. However, the disclosure is not limited thereto and the number of devices and/or the number of unique measurement data may vary without departing from the disclosure.

As illustrated in FIG. 9, the measurement data **910** may include information associated with each of the other devices **410/412**, such as an AOA value, a variance associated with the AOA value, and/or timing information corresponding to first peak(s). However, this is intended to conceptually illustrate an example and the disclosure is not limited thereto. Additionally or alternatively, the measurement data **910** may include information associated with user speech (e.g., AOA value and associated variance) and/or information associated with the television (e.g., AOA and variance associated with a left channel and a right channel of the television), although the disclosure is not limited thereto.

Using the measurement data **910**, the matrix solver component **920** may perform localization and generate device map data **925** indicating location(s) associated with each of the devices **410/412**, a location of a television, a location of a listening position **210**, and/or the like. A coordinate transform component **930** may transform the device map data **925** into final device map data **935**. For example, the coordinate transform component **930** may generate the final device map data **935** using a fixed perspective, such that the listening position **210** is at the origin (e.g., intersection between the horizontal axis and the vertical axis in a two-dimensional plane) and the user's look direction (e.g., direction between the listening position **210** and the television) is along the vertical axis. Using this frame of reference, the coordinate transform component **930** may transform the locations (e.g., [x,y] coordinates) such that each coordinate value indicates a distance from the listening position **210** along the horizontal and/or vertical axis.

While not illustrated in FIG. 9, the system **100** may use the timing information to determine distance values between each of the devices **410/412**. For example, the system **100** may use the timing information to estimate a propagation delay from one device to another device, which enables the system **100** to estimate the distance between the two devices. In some examples, the matrix solver component **920** may be configured to determine the distance values as part of generating the device map data **925**. For example, the matrix solver component **920** may receive the measurement data **910** and determine the distance values using the timing information included within the measurement data **910** without departing from the disclosure. Additionally or alternatively, another component may be configured to determine the distance values prior to the matrix solver component **920** generating the device map data **925**. For example, an additional component (not illustrated) may receive the timing information and determine the distance values without

departing from the disclosure. Thus, the measurement data **910** may include the distance values and/or the matrix solver component **920** may receive the distance values from the additional component, although the disclosure is not limited thereto.

In some examples, the distance values may be associated with confidence values indicating a likelihood that the distance values are accurate. For example, the system **100** may generate the distance values based on timing information associated with multiple microphones on an individual device. If the timing information is relatively consistent between the multiple microphones, such as when a variance is low, a measure of similarity is relatively high, and/or the like, the system **100** may associate the distance value with a high confidence value that indicates a high likelihood that the distance value is accurate. However, if the timing information varies between the multiple microphones, such that the variance is high, the measure of similarity is relatively low, and/or the like, then the system **100** may associate the distance value with a low confidence value that indicates a low likelihood that the distance value is accurate. In some examples, the system **100** may discard distance values associated with confidence values below a threshold without departing from the disclosure. However, the disclosure is not limited thereto and in other examples the matrix solver component **920** may receive the confidence values along with the distance values and use the confidence values to generate the device map data **925** without departing from the disclosure.

In some examples, the device map data **925** may correspond to two-dimensional (2D) coordinates, such as a top-level map of a room. However, the disclosure is not limited thereto, and in other examples the device map data **925** may correspond to three dimensional (3D) coordinates without departing from the disclosure. Additionally or alternatively, the device map data **925** may indicate locations using relative positions, such as representing a relative location using an angle and/or distance from a reference point (e.g., device location) without departing from the disclosure. However, the disclosure is not limited thereto, and the device map data **925** may represent locations using other techniques without departing from the disclosure.

FIGS. 10A-10B illustrate examples of calibration sound playback and calibration sound capture according to embodiments of the present disclosure. As described above, the primary device **410** may generate calibration data indicating an order in which the secondary devices **412** will generate playback audio during a calibration sequence. For example, the calibration data may indicate that a first device (Device1) will generate a first audible sound during a first time range, a second device (Device2) will generate a second audible sound during a second time range, a third device (Device3) will generate a third audible sound during a third time range, and a fourth device (Device4) will generate a fourth audible sound during a fourth time range.

While FIG. 5 illustrates a conceptual example of a calibration playback schedule and corresponding calibration sound capture, FIGS. 10A-10B illustrate actual waveforms being output by the loudspeakers and/or captured by the microphones of the devices during the calibration sequence. For example, calibration playback **1010** illustrates examples of actual waveforms being output by the loudspeakers. While all four devices are listening and capturing audio during the entire calibration sequence, the devices only generate audible sounds during the designated time range indicated by the calibration data.

As illustrated in FIG. 10A, the first device only generates an audible sound during the first time range, as shown by Device 1 Output **1020a**, the second device only generates an audible sound during the second time range, as illustrated by Device 2 Output **1020b**, the third device only generates an audible sound during the third time range, as illustrated by Device 3 Output **1020c**, and the fourth device only generates an audible sound during the fourth time range, as illustrated by Device 4 Output **1020d**.

As illustrated in FIG. 10B, during calibration capture **1030** the devices **110** capture input audio and generate audio data during the entire calibration sequence, including when each device is generating the audible sound. For example, Device 1 Capture **1040a** illustrates that the first device captures a first representation of the first audible sound during the first time range, a first representation of the second audible sound during the second time range, a first representation of the third audible sound during the third time range, and a first representation of the fourth audible sound during the fourth time range. Similarly, Device 2 Capture **1040b** illustrates that the second device captures a second representation of the first audible sound during the first time range, a second representation of the second audible sound during the second time range, a second representation of the third audible sound during the third time range, and a second representation of the fourth audible sound during the fourth time range. Device 3 Capture **1040c** and Device 4 Capture **1040d** illustrate similar waveforms for the third device and the fourth device, respectively.

The system **100** may determine a distance between a pair of devices based on a time difference between when the pair of devices capture the audible sounds generated by the pair of devices. For example, the system **100** may determine a first distance between the first device and the second device by comparing a first time difference between when the first device captures the first representation of the first audible sound and the first representation of the second audible sound with a second time difference between when the second device captures the second representation of the first audible sound and the second representation of the second audible sound. Similarly, the system **100** may determine a second distance between the first device and the third device by comparing a third time difference between when the first device captures the first representation of the first audible sound and the first representation of the third audible sound with a fourth time difference between when the third device captures the third representation of the first audible sound and the third representation of the third audible sound. Thus, based on the calibration sequence, the system **100** may compare any pair of devices and use timing information corresponding to the pair of devices to determine a distance between the two devices without departing from the disclosure.

FIGS. 11A-11C illustrate examples of calibration timing information that is used to determine distance values according to embodiments of the present disclosure. The system **100** may determine time differences represented in the timing information and may determine distance values between secondary devices using the time differences. For example, to determine a distance between the first device (e.g., Device A) and the second device (e.g., Device B), the system **100** may determine a first time difference between when the first device detected a first audible sound generated by the first device and when the first device detected a second audible sound generated by the second device. Similarly, the system **100** may determine a second time difference between when the second device detected the first

audible sound generated by the first device and when the second device detected the second audible sound generated by the second device. By subtracting the second time difference from the first time difference and dividing in half, the system 100 may determine a propagation delay from the first device to the second device and a corresponding distance value. Thus, the system 100 may perform similar processing between each pair of devices to determine the distance values.

FIG. 11A illustrates an example of first calibration timing 1100 illustrating timing information associated with a first pair of devices (e.g., Device A and Device B). As illustrated in FIG. 11A, the calibration schedule may instruct the devices to generate an audible sound in a fixed sequence, such that Device A generates a first audible sound during a first time range, Device B generates a second audible sound during a second time range, Device C generates a third audible sound during a third time range, and Device D generates a fourth audible sound during a fourth time range. In the example illustrated in FIG. 11A, the sequence restarts and Device A generates a fifth audible sound during a fifth time range, although the disclosure is not limited thereto.

The first calibration timing 1100 illustrates the timing of when each of the devices captures each of the audible sounds. As Device A generated the first audible sound, Device A is the first to capture the first audible sound. For example, the first calibration timing 1100 illustrates that Device A captures the first audible sound at time t_{AA} , Device B captures the first audible sound at time t_{AB} , Device D captures the first audible sound at time t_{AD} , and then Device C captures the first audible sound at time t_{AC} .

Similarly, as Device B generated the second audible sound, Device B is the first to capture the second audible sound. For example, the first calibration timing 1100 illustrates that Device B captures the second audible sound at time t_{BB} , Device A captures the second audible sound at time t_{BA} , Device C captures the second audible sound at time t_{BC} , and then Device D captures the second audible sound at time t_{BD} . Likewise, the first calibration timing 1100 illustrates that Device C captures the third audible sound at time t_{CC} , Device D captures the third audible sound at time t_{CD} , Device B captures the third audible sound at time t_{CB} , and then Device A captures the third audible sound at time t_{CA} .

As illustrated in FIG. 11A, the first calibration timing 1100 illustrates that Device D captures the fourth audible sound at time t_{DD} , Device B captures the fourth audible sound at time t_{DB} , Device A captures the fourth audible sound at time t_{DA} , and then Device C captures the fourth audible sound at time t_{DC} . Finally, the first calibration timing 1100 illustrates that Device A captures the fifth audible sound at time t'_{AA} , Device B captures the fifth audible sound at time t'_{AB} , Device D captures the fifth audible sound at time t'_{AD} , and then Device C captures the fifth audible sound at time t'_{AC} .

To determine a first distance value between Device A and Device B, the system 100 may determine a first time difference τ_{AABA} between when Device A captures the first audible sound (t_{AA}) and when Device A captures the second audible sound (t_{BA}). Similarly, the system 100 may determine a second time difference τ_{ABBB} between when Device B captures the first audible sound (t_{AB}) and when Device B captures the second audible sound (t_{BB}). As illustrated in FIG. 11A, the second time difference τ_{ABBB} is a shorter duration than the first time difference τ_{AABA} . Thus, the system 100 may determine a first combined propagation delay between Device A and Device B by subtracting the second time difference τ_{ABBB} from the first time difference

τ_{AABA} . To determine the first distance value, the system 100 may assume that the propagation delay from Device A to Device B (e.g., τ_{AB}) is equal to the propagation delay from Device B to Device A (τ_{BA}) and divide the first combined propagation delay in half. Thus, the system 100 may calculate the first distance value based on the first combined propagation delay and a known constant value corresponding to the speed of sound.

FIG. 11B illustrates an example of second calibration timing 1110 illustrating timing information associated with a second pair of devices (e.g., Device A and Device C). To determine a second distance value between Device A and Device C, the system 100 may determine a third time difference τ_{AAC_A} between when Device A captures the first audible sound (t_{AA}) and when Device A captures the third audible sound (t_{CA}). Similarly, the system 100 may determine a fourth time difference τ_{ACCC} between when Device C captures the first audible sound (t_{AC}) and when Device C captures the third audible sound (t_{CC}). As illustrated in FIG. 11B, the fourth time difference τ_{ACCC} is a shorter duration than the third time difference τ_{AAC_A} . Thus, the system 100 may determine a second combined propagation delay between Device A and Device C by subtracting the fourth time difference τ_{ACCC} from the third time difference τ_{AAC_A} . To determine the second distance value, the system 100 may assume that the propagation delay from Device A to Device C (e.g., τ_{AC}) is equal to the propagation delay from Device C to Device A (τ_{CA}) and divide the second combined propagation delay in half. Thus, the system 100 may calculate the second distance value based on the second combined propagation delay and a known constant value corresponding to the speed of sound.

In some examples, the system 100 may perform the same process to determine a third distance value between Device A and Device D. For example, the system 100 may determine timing information between when each of Devices A/D capture the first audible sound and the fourth audible sound. However, the disclosure is not limited thereto and in some examples, the system 100 may perform an inverse process to determine the third distance value, as illustrated in FIG. 11C.

FIG. 11C illustrates an example of third calibration timing 1120 illustrating timing information associated with a third pair of devices (e.g., Device A and Device D). To determine a third distance value between Device A and Device D, the system 100 may determine a fifth time difference τ_{DDAD} between when Device D captures the fourth audible sound (t_{DD}) and when Device D captures the fifth audible sound (t'_{AD}). Similarly, the system 100 may determine a sixth time difference τ_{DAAA} between when Device A captures the fourth audible sound (t_{DA}) and when Device A captures the fifth audible sound (t'_{AA}). As illustrated in FIG. 11C, the sixth time difference τ_{DAAA} is a shorter duration than the fifth time difference τ_{DDAD} . Thus, the system 100 may determine a third combined propagation delay between Device A and Device D by subtracting the sixth time difference τ_{DAAA} from the fifth time difference τ_{DDAD} . To determine the third distance value, the system 100 may assume that the propagation delay from Device D to Device A (e.g., τ_{DA}) is equal to the propagation delay from Device A to Device D (τ_{AD}) and divide the third combined propagation delay in half. Thus, the system 100 may calculate the third distance value based on the third combined propagation delay and the known constant value corresponding to the speed of sound.

FIG. 12 illustrates an example component diagram for performing device mapping according to embodiments of the present disclosure. As illustrated in FIG. 12, device mapping 1200 may include local components that perform

local processing on each of the secondary devices 412 and centralized components that perform global processing on the primary device 410. For example, each of the devices 110 may include a distance estimation local processing component 1220 and an acoustic wave decomposition (AWD) local processing component 1230 that are configured to generate the timing information and/or azimuth data. To determine the distance information, however, the primary device 410 may include a distance estimation global processing component 1240 configured to determine time differences represented in the timing information and estimate the distance values based on the time differences.

As illustrated in FIG. 12, the distance estimation local processing component 1220 may receive a stimulus 1205 (e.g., stimulus data) corresponding to the calibration tone, microphone audio data 1210 generated by one or more microphones of the local device, and expected peak data 1222. Using these inputs, the distance estimation local processing component 1220 may determine start/end times 1222 and/or timing information 1224. As illustrated in FIG. 12, the distance estimation local processing component 1220 may output the start/end times 1222 to the AWD local processing component 1230 and may output the timing information 1224 to the distance estimation global processing component 1240 on the primary device 410.

In some examples, the expected peak data 1215 may correspond to expected locations at which the system 100 expects to detect peaks based on a repeating pattern associated with the calibration sequence. For example, if the calibration sequence has a repeating structure, such as a consistent duration of time between stimulus playback and the stimulus signal, the system 100 may predict when peaks corresponding to the stimulus signal will occur. However, the system 100 may only generate the expected peak data 1215 based on knowledge of timing associated with a first stimulus. Thus, the distance estimation local processing component 1220 may generate the start/end times 1222 and/or the timing information 1224 without using the expected peak data 1215 without departing from the disclosure. Additionally or alternatively, in some examples the expected peak data 1215 may indicate a number of devices included in the calibration sequence, such that the distance estimation local processing component 1220 may determine a number of peaks that will be represented in a particular time interval. The AWD local processing component may receive the start/end times 1222 from the distance estimation local processing component 1220 and may use the start/end times 1222 and the microphone audio data 1210 associated with the local device to generate direction data 1235 indicating relative directions associated with the devices. Thus, the AWD local processing component 1230 may output the direction data 1235 to the primary device 410.

The distance estimation global processing component 1240 included in the primary device 410 may receive timing information 1224 from each of the secondary devices 412. For example, the distance estimation global processing component 1240 may receive first timing information 1224a from the first secondary device 412a, second timing information 1224b from the second secondary device 412b, third timing information 1224c from the third secondary device 412c, and so on. The distance estimation global processing component 1240 may use the timing information 1224 to generate a range matrix 1242 representing relative distance values between the devices and confidence data 1244 representing a likelihood that the distance values are accurate. For example, the distance estimation global processing component 1240 may compare the timing information gen-

erated by multiple devices in order to generate the range matrix 1242 representing the distance values and the confidence data 1244 and may output the range matrix 1242 and the confidence data 1244 to a solver component 1250.

Finally, the solver component 1250 may be configured to receive the range matrix 1242, the confidence data 1244, and/or the direction data (e.g., azimuth information) from the secondary devices 412 and may generate device map data 1255.

The confidence data 1244 may represent confidence values that correspond to a measure of confidence in the distance values included in the range matrix 1242. In some examples, the system 100 may use the confidence data 1244 to identify whether the distance values are accurate or should be discarded. For example, the system 100 may discard distance values that are associated with confidence values below a threshold. However, the disclosure is not limited thereto and in other examples, the solver component 1250 may use the confidence data 1244 as an additional input to generate the device map data 1255. For example, the solver component 1250 may have a probabilistic framework that takes the confidence data 1244 into account and adjusts a weight value for a distance value based on a corresponding confidence value (e.g., increases a first weight associated with a high confidence value, or decreases a second weight associated with a low confidence value), although the disclosure is not limited thereto.

FIG. 13 illustrates an example component diagram for performing distance estimation according to embodiments of the present disclosure. As illustrated in FIG. 13, the system 100 may perform distance estimation 1300 using the distance estimation local processing components 1220 associated with multiple secondary devices 412 and the distance estimation global processing component 1240 described above with regard to FIG. 12. For example, the distance estimation local processing component 1220 may include a cross-correlation component 1320 configured to generate a cross-correlation between the stimulus 1205 and the microphone audio data 1210. FIG. 14A illustrates an example of raw device capture 1410, which represents the microphone audio data 1210, and raw cross-correlation 1420, which illustrates an example of cross-correlation data. However, the system 100 may normalize the cross-correlation data and generate rolling-norm cross-correlation 1430, illustrated in FIG. 14B.

To perform peak detection, the system 100 may generate a dynamic threshold, represented as a gray line in the rolling-norm cross-correlation 1430. For example, a peak location component 1330 may locate peaks represented in the cross-correlation data and a peak selection component 1340 may filter and select the peaks from the cross-correlation data. In some examples, the distance estimation local processing component 1220 may generate the dynamic threshold using a percentile tracker. For example, the distance estimation local processing component 1220 may track a pth percentile (e.g., 99 th percentile) and generate the dynamic threshold using the pth percentile, although the disclosure is not limited thereto.

As illustrated in FIG. 14B, the system 100 may identify a first peak represented in the cross-correlation data by identifying the first peak that cross the dynamic threshold. For example, first peak detection 1440 illustrates a portion of the rolling-norm cross-correlation 1430 where the cross-correlation data first exceeds the dynamic threshold. Thus, the distance estimation local processing component 1220 may perform match filtering and peak filtering to generate the timing information for an individual microphone channel.

In some examples, the distance estimation local processing component 1220 may generate timing information for each of the microphone channels. For example, if the secondary device 412 includes seven microphones, the distance estimation local processing component 1220 may generate timing information for each of the seven microphone channels. However, the disclosure is not limited thereto and in other examples the distance estimation local processing component 1220 may generate the timing information for a subset of the microphone channels without departing from the disclosure. For example, the distance estimation local processing component 1220 may generate timing information for only four of the seven microphone channels without departing from the disclosure. The timing information for each individual microphone channel will identify peaks associated with each of the audible sounds captured in the microphone audio data 1210. Thus, if there are four devices included in the calibration sequence, the timing information may identify four peaks, although the disclosure is not limited thereto.

In some examples, the distance estimation local processing component 1220 may perform additional processing to the microphone audio data 1210 when the local device generates the audible sound. For example, the distance estimation local processing component 1220 may account for a distance between each loudspeaker of the local device and an individual microphone channel. By adjusting for these loudspeaker to microphone distances, the system 100 may improve an accuracy of the timing information and/or reduce an error in estimating the distance values, although the disclosure is not limited thereto. In order to adjust for these loudspeaker to microphone distances, the system 100 may require prior knowledge of device dimensions and/or locations of the loudspeaker(s) and microphone(s) of the local device.

FIG. 15 is a flowchart conceptually illustrating an example method for performing distance estimation according to embodiments of the present disclosure. As illustrated in FIG. 15, the system 100 may receive (1510) timing information and select (1512) a pair of devices (e.g., first device and second device). Using the timing information associated with the pair of devices, the system 100 may determine (1514) a first time difference from when the first device detects a first audible sound (e.g., generated by the first device) and when the first device detects a second audible sound (e.g., generated by the second device). Similarly, the system 100 may determine (1516) a second time difference from when the second device detects the first audible sound and when the second device detects the second audible sound. The system 100 may then determine (1518) a distance value between the first device and the second device.

The system 100 may determine (1520) whether there is an additional pair of devices and, if so, may loop to step 1512 and repeat steps 1512-1518 for the additional pair of devices. If the system 100 determines that there is not an additional pair of devices, the system 100 may generate (1522) distance data representing the distance values determined in step 1518.

FIG. 16 is a block diagram conceptually illustrating a device 110 that may be used with the remote system 120. FIG. 17 is a block diagram conceptually illustrating example components of a remote device, such as the remote system 120, which may assist with ASR processing, NLU processing, etc.; and a skill component 125. A system (120/125) may include one or more servers. A “server” as used herein may refer to a traditional server as understood in a server/

client computing structure but may also refer to a number of different computing components that may assist with the operations discussed herein. For example, a server may include one or more physical computing components (such as a rack server) that are connected to other devices/components either physically and/or over a network and is capable of performing computing operations. A server may also include one or more virtual machines that emulates a computer system and is run on one or across multiple devices. A server may also include other combinations of hardware, software, firmware, or the like to perform operations discussed herein. The remote system 120 may be configured to operate using one or more of a client-server model, a computer bureau model, grid computing techniques, fog computing techniques, mainframe techniques, utility computing techniques, a peer-to-peer model, sandbox techniques, or other computing techniques.

Multiple systems (120/125) may be included in the system 100 of the present disclosure, such as one or more remote systems 120 for performing ASR processing, one or more remote systems 120 for performing NLU processing, and one or more skill component 125, etc. In operation, each of these systems may include computer-readable and computer-executable instructions that reside on the respective device (120/125), as will be discussed further below.

Each of these devices (110/120/125) may include one or more controllers/processors (1604/1704), which may each include a central processing unit (CPU) for processing data and computer-readable instructions, and a memory (1606/1706) for storing data and instructions of the respective device. The memories (1606/1706) may individually include volatile random access memory (RAM), non-volatile read only memory (ROM), non-volatile magnetoresistive memory (MRAM), and/or other types of memory. Each device (110/120/125) may also include a data storage component (1608/1708) for storing data and controller/processor-executable instructions. Each data storage component (1608/1708) may individually include one or more non-volatile storage types such as magnetic storage, optical storage, solid-state storage, etc. Each device (110/120/125) may also be connected to removable or external non-volatile memory and/or storage (such as a removable memory card, memory key drive, networked storage, etc.) through respective input/output device interfaces (1602/1702).

Computer instructions for operating each device (110/120/125) and its various components may be executed by the respective device's controller(s)/processor(s) (1604/1704), using the memory (1606/1706) as temporary “working” storage at runtime. A device's computer instructions may be stored in a non-transitory manner in non-volatile memory (1606/1706), storage (1608/1708), or an external device(s). Alternatively, some or all of the executable instructions may be embedded in hardware or firmware on the respective device in addition to or instead of software.

Each device (110/120/125) includes input/output device interfaces (1602/1702). A variety of components may be connected through the input/output device interfaces (1602/1702), as will be discussed further below. Additionally, each device (110/120/125) may include an address/data bus (1624/1724) for conveying data among components of the respective device. Each component within a device (110/120/125) may also be directly connected to other components in addition to (or instead of) being connected to other components across the bus (1624/1724).

Referring to FIG. 16, the device 110 may include input/output device interfaces 1602 that connect to a variety of components such as an audio output component such as a

speaker **1612**, a wired headset or a wireless headset (not illustrated), or other component capable of outputting audio. The device **110** may also include an audio capture component. The audio capture component may be, for example, a microphone **1620** or array of microphones, a wired headset or a wireless headset (not illustrated), etc. If an array of microphones is included, approximate distance to a sound's point of origin may be determined by acoustic localization based on time and amplitude differences between sounds captured by different microphones of the array. The device **110** may additionally include a display **1616** for displaying content. The device **110** may further include a camera **1618**.

Via antenna(s) **1614**, the input/output device interfaces **1602** may connect to one or more networks **199** via a wireless local area network (WLAN) (such as Wi-Fi) radio, Bluetooth, and/or wireless network radio, such as a radio capable of communication with a wireless communication network such as a Long Term Evolution (LTE) network, WiMAX network, 3G network, 4G network, 5G network, etc. A wired connection such as Ethernet may also be supported. Through the network(s) **199**, the system may be distributed across a networked environment. The I/O device interface (**1602/1702**) may also include communication components that allow data to be exchanged between devices such as different physical servers in a collection of servers or other components.

The components of the device **110**, the remote system **120**, and/or a skill component **125** may include their own dedicated processors, memory, and/or storage. Alternatively, one or more of the components of the device **110**, the remote system **120**, and/or a skill component **125** may utilize the I/O interfaces (**1602/1702**), processor(s) (**1604/1704**), memory (**1606/1706**), and/or storage (**1608/1708**) of the device(s) **110**, system **120**, or the skill component **125**, respectively. Thus, the ASR component **250** may have its own I/O interface(s), processor(s), memory, and/or storage; the NLU component **260** may have its own I/O interface(s), processor(s), memory, and/or storage; and so forth for the various components discussed herein.

As noted above, multiple devices may be employed in a single system. In such a multi-device system, each of the devices may include different components for performing different aspects of the system's processing. The multiple devices may include overlapping components. The components of the device **110**, the remote system **120**, and a skill component **125**, as described herein, are illustrative, and may be located as a stand-alone device or may be included, in whole or in part, as a component of a larger device or system.

As illustrated in FIG. 18, multiple devices (**110a-110k**, **120**, **125**) may contain components of the system and the devices may be connected over a network(s) **199**. The network(s) **199** may include a local or private network or may include a wide network such as the Internet. Devices may be connected to the network(s) **199** through either wired or wireless connections. For example, a speech-detection device **110a**, a smart phone **110b**, a smart watch **110c**, a tablet computer **110d**, a speech-detection device **110e**, a display device **110f**, a smart television **110g**, a headless device **110h**, and/or a mobile device **110i** may be connected to the network(s) **199** through a wireless service provider, over a Wi-Fi or cellular network connection, or the like. Other devices are included as network-connected support devices, such as the remote system **120**, the skill component(s) **125**, and/or others. The support devices may connect to the network(s) **199** through a wired connection or a wireless connection. Networked devices may capture audio

using one-or-more built-in or connected microphones or other audio capture devices, with processing performed by ASR components, NLU components, or other components of the same device or another device connected via the network(s) **199**, such as the ASR component **250**, the NLU component **260**, etc. of the remote system **120**.

The concepts disclosed herein may be applied within a number of different devices and computer systems, including, for example, general-purpose computing systems, speech processing systems, and distributed computing environments.

The above aspects of the present disclosure are meant to be illustrative. They were chosen to explain the principles and application of the disclosure and are not intended to be exhaustive or to limit the disclosure. Many modifications and variations of the disclosed aspects may be apparent to those of skill in the art. Persons having ordinary skill in the field of computers and speech processing should recognize that components and process steps described herein may be interchangeable with other components or steps, or combinations of components or steps, and still achieve the benefits and advantages of the present disclosure. Moreover, it should be apparent to one skilled in the art, that the disclosure may be practiced without some or all of the specific details and steps disclosed herein.

Aspects of the disclosed system may be implemented as a computer method or as an article of manufacture such as a memory device or non-transitory computer readable storage medium. The computer readable storage medium may be readable by a computer and may comprise instructions for causing a computer or other device to perform processes described in the present disclosure. The computer readable storage medium may be implemented by a volatile computer memory, non-volatile computer memory, hard drive, solid-state memory, flash drive, removable disk, and/or other media. In addition, components of system may be implemented as in firmware or hardware, such as an acoustic front end (AFE), which comprises, among other things, analog and/or digital filters (e.g., filters configured as firmware to a digital signal processor (DSP)).

Conditional language used herein, such as, among others, "can," "could," "might," "may," "e.g., and the like, unless specifically stated otherwise, or otherwise understood within the context as used, is generally intended to convey that certain embodiments include, while other embodiments do not include, certain features, elements and/or steps. Thus, such conditional language is not generally intended to imply that features, elements, and/or steps are in any way required for one or more embodiments or that one or more embodiments necessarily include logic for deciding, with or without other input or prompting, whether these features, elements, and/or steps are included or are to be performed in any particular embodiment. The terms "comprising," "including," "having," and the like are synonymous and are used inclusively, in an open-ended fashion, and do not exclude additional elements, features, acts, operations, and so forth. Also, the term "or" is used in its inclusive sense (and not in its exclusive sense) so that when used, for example, to connect a list of elements, the term "or" means one, some, or all of the elements in the list.

Disjunctive language such as the phrase "at least one of X, Y, Z," unless specifically stated otherwise, is understood with the context as used in general to present that an item, term, etc., may be either X, Y, or Z, or any combination thereof (e.g., X, Y, and/or Z). Thus, such disjunctive language is not generally intended to, and should not, imply that

29

certain embodiments require at least one of X, at least one of Y, or at least one of Z to each be present.

As used in this disclosure, the term “a” or “one” may include one or more items unless specifically stated otherwise. Further, the phrase “based on” is intended to mean “based at least in part on” unless specifically stated otherwise.

What is claimed is:

1. A computer-implemented method, the method comprising:
  - generating, by a first device, a first audible sound;
  - generating, by a second device, a second audible sound;
  - generating, by the first device, first audio data representing audio captured by a first microphone of the first device, the first audio data including a first representation of the first audible sound and a first representation of the second audible sound;
  - generating, by the first device, second audio data representing audio captured by a second microphone of the first device, the second audio data including a second representation of the first audible sound and a second representation of the second audible sound;
  - generating, by the second device, third audio data representing audio captured by the second device, the third audio data including a third representation of the first audible sound and a third representation of the second audible sound;
  - generating, by the first device using the first audio data and the second audio data, first data indicating a first time associated with the first device’s detection of the first audible sound, a second time associated with the first device’s detection of the second audible sound, a first variance associated with the first time, and a second variance associated with the second time;
  - generating, by the second device using the third audio data, second data indicating a third time associated with the second device’s detection of the first audible sound and a fourth time associated with the second device’s detection of the second audible sound;
  - sending, by the first device to a third device, the first data;
  - sending, by the second device to the third device, the second data;
  - determining, by the third device using the first data, a first time difference between the first time and the second time;
  - determining, by the third device using the second data, a second time difference between the third time and the fourth time;
  - determining, by the third device using the first time difference and the second time difference, a first distance value representing a distance from the first device to the second device; and
  - determining, by the third device, a confidence value corresponding to the first distance value, wherein the confidence value is determined using at least the first data and the second data.
2. The computer-implemented method of claim 1, wherein the first data indicates a fifth time associated with the first device’s detection of a third audible sound generated by a fourth device and a sixth time associated with the first device’s detection of a fourth audible sound generated by the first device, the method further comprising:
  - receiving, by the third device from the fourth device, third data indicating a seventh time associated with the fourth device’s detection of the first audible sound, an eighth time associated with the fourth device’s detection of the third audible sound, and a ninth time associated with the fourth device’s detection of the fourth audible sound;
  - determining, by the third device using the first data, a third time difference from the fifth time and the sixth time;
  - determining, by the third device using the third data, a fourth time difference from the eighth time and the ninth time; and
  - determining, by the third device using the third time difference and the fourth time difference, a second distance value representing a second distance from the first device to the fourth device.
3. The computer-implemented method of claim 1, wherein determining the first distance value further comprises:
  - determining a third time difference by subtracting the second time difference from the first time difference;
  - determining a fourth time difference by dividing the third time difference in half; and
  - determining the first distance value by dividing the fourth time difference by a value representing a speed of sound.
4. The computer-implemented method of claim 1, further comprising:
  - generating, by the third device, fourth data using the first distance value, the fourth data indicating a first location associated with the first device and a second location associated with the second device;
  - generating, by the third device and using the fourth data, first coefficient values corresponding to the first device;
  - generating, by the third device and using the fourth data, second coefficient values corresponding to the second device;
  - sending, by the third device to the first device, the first coefficient values, wherein the first device generates first audio based on the first coefficient values; and
  - sending, by the third device to the second device, the second coefficient values, wherein the second device generates second audio based on the second coefficient values.
5. A computer-implemented method, the method comprising:
  - sending, by a first device to a second device and a third device, first data instructing (i) the second device to generate a first sound during a first time range and (ii) the third device to generate a second sound during a second time range;
  - receiving, by the first device from the second device, first time data indicating when a first microphone of the second device detected the first sound, second time data indicating when the first microphone of the second device detected the second sound, third time data indicating when a second microphone of the second device detected the first sound, and fourth time data indicating when the second microphone of the second device detected the second sound;
  - receiving, by the first device from the third device, fifth time data indicating when the third device detected the first sound and sixth time data indicating when the third device detected the second sound;
  - determining, by the first device, a first time difference between the first time data and the second time data;
  - determining, by the first device, a second time difference between the fifth time data and the sixth time data;
  - determining, by the first device using the first time difference and the second time difference, a first distance

30

tion of the third audible sound, and a ninth time associated with the fourth device’s detection of the fourth audible sound;

determining, by the third device using the first data, a third time difference from the fifth time and the sixth time;

determining, by the third device using the third data, a fourth time difference from the eighth time and the ninth time; and

determining, by the third device using the third time difference and the fourth time difference, a second distance value representing a second distance from the first device to the fourth device.

3. The computer-implemented method of claim 1, wherein determining the first distance value further comprises:

determining a third time difference by subtracting the second time difference from the first time difference;

determining a fourth time difference by dividing the third time difference in half; and

determining the first distance value by dividing the fourth time difference by a value representing a speed of sound.

4. The computer-implemented method of claim 1, further comprising:

generating, by the third device, fourth data using the first distance value, the fourth data indicating a first location associated with the first device and a second location associated with the second device;

generating, by the third device and using the fourth data, first coefficient values corresponding to the first device;

generating, by the third device and using the fourth data, second coefficient values corresponding to the second device;

sending, by the third device to the first device, the first coefficient values, wherein the first device generates first audio based on the first coefficient values; and

sending, by the third device to the second device, the second coefficient values, wherein the second device generates second audio based on the second coefficient values.

5. A computer-implemented method, the method comprising:

sending, by a first device to a second device and a third device, first data instructing (i) the second device to generate a first sound during a first time range and (ii) the third device to generate a second sound during a second time range;

receiving, by the first device from the second device, first time data indicating when a first microphone of the second device detected the first sound, second time data indicating when the first microphone of the second device detected the second sound, third time data indicating when a second microphone of the second device detected the first sound, and fourth time data indicating when the second microphone of the second device detected the second sound;

receiving, by the first device from the third device, fifth time data indicating when the third device detected the first sound and sixth time data indicating when the third device detected the second sound;

determining, by the first device, a first time difference between the first time data and the second time data;

determining, by the first device, a second time difference between the fifth time data and the sixth time data;

determining, by the first device using the first time difference and the second time difference, a first distance

31

value representing a distance between the second device and the third device; and determining, by the first device, a first confidence value corresponding to the first distance value, wherein the first confidence value is determined using at least the first time data, the second time data, the third time data, the fourth time data, the fifth time data, and the sixth time data.

6. The computer-implemented method of claim 5, further comprising:

generating, by the first device, fourth data using the first distance value, the fourth data indicating a first location associated with the second device and a second location associated with the third device;

generating, by the first device and using the fourth data, first coefficient values corresponding to the second device;

generating, by the first device and using the fourth data, second coefficient values corresponding to the third device;

sending, by the first device to the second device, the first coefficient values, wherein the second device generates first output audio using the first coefficient values; and sending, by the first device to the third device, the second coefficient values, wherein the third device generates second output audio using the second coefficient values.

7. The computer-implemented method of claim 5, wherein the first time data and the second time data is generated using a first clock associated with the second device, the fifth time data and the sixth time data is generated using a second clock associated with the third device, and the first clock is not synchronized with the second clock.

8. The computer-implemented method of claim 5, further comprising:

receiving, by the first device from the second device, seventh time data indicating when the first microphone of the second device detected a third sound generated by a fourth device;

receiving, by the first device from the fourth device, eighth time data indicating when the fourth device detected the first sound and ninth time data indicating when the fourth device detected the third sound;

determining, by the first device, a third time difference between the first time data and the seventh time data;

determining, by the first device, a fourth time difference between the eighth time data and the ninth time data; and

determining, by the first device using the third time difference and the fourth time difference, a second distance value representing a distance between the second device and the fourth device.

9. The computer-implemented method of claim 5, further comprising:

receiving, by the first device from the second device, seventh time data indicating when the first microphone of the second device detected a third sound generated by a fourth device and eighth time data indicating when the first microphone of the second device detected a fourth sound generated by the second device;

receiving, by the first device from the fourth device, ninth time data indicating when the fourth device detected the first sound, tenth time data indicating when the fourth device detected the third sound, and eleventh time data indicating when the fourth device detected the fourth sound;

32

determining, by the first device, a third time difference between the seventh time data and the eighth time data; determining, by the first device, a fourth time difference between the tenth time data and the eleventh time data; and

determining, by the first device using the third time difference and the fourth time difference, a second distance value representing a distance between the second device and the fourth device.

10. The computer-implemented method of claim 5, wherein determining the first distance value further comprises:

determining a third time difference by subtracting the second time difference from the first time difference; determining a fourth time difference by dividing the third time difference in half; and

determining the first distance value by dividing the fourth time difference by a value representing a speed of sound.

11. The computer-implemented method of claim 5, further comprising:

generating fourth data including at least the first distance value, a second distance value between the second device and a fourth device, and a third distance value between the third device and the fourth device; and determining, using the fourth data, fifth data indicating an arrangement of the second device, the third device, and the fourth device.

12. The computer-implemented method of claim 5, further comprising:

generating, by the second device, the first sound;

generating, by the third device, the second sound;

generating, by the second device, first audio data representing audio captured by the second device, the first audio data including a first representation of the first sound and a first representation of the second sound;

generating, by the third device, second audio data representing audio captured by the third device, the second audio data including a second representation of the first sound and a second representation of the second sound;

generating, by the second device using the first audio data, the first time data and the second time data; and

generating, by the third device using the second audio data, the fifth time data and the sixth time data.

13. The computer-implemented method of claim 5, further comprising:

generating, by the first device, fourth data including at least the first distance value and a second distance value between the second device and a fourth device;

generating, by the first device, fifth data including at least the first confidence value and a second confidence value corresponding to the second distance value; and

determining, using the fourth data and the fifth data, sixth data indicating a first location associated with the second device, a second location associated with the third device, and a third location associated with the fourth device.

14. The computer-implemented method of claim 5, further comprising:

determining, by the first device, that the first confidence value is below a threshold value;

determining, by the first device using the first time data and seventh time data received from a fourth device, a second distance value representing a second distance between the second device and the fourth device;

determining, by the first device, a second confidence value corresponding to the second distance value;

determining, by the first device, that the second confidence value exceeds the threshold value; and determine, using at least the second distance value, fourth data indicating an arrangement of a plurality of devices that includes the second device, the third device, and the fourth device. 5

15. The computer-implemented method of claim 5, wherein:

the first time data corresponds to a first peak represented in cross-correlation data. 10

16. The computer-implemented method of claim 5, wherein:

the first time data comprises a plurality of timestamps. 15

17. The computer-implemented method of claim 5, wherein:

the first time data comprises statistical information based on at least one timestamp. 15
